UNITED STATES PATENT OFFICE.

BAY H. CLIFTON, OF EAST PERU, IOWA, ASSIGNOR TO UNIVERSAL MANUFACTURING COMPANY, OF DES MOINES, IOWA, A CORPORATION OF IOWA.

TIMING DEVICE.

1,356,968.

Specification of Letters Patent. Patented Oct. 26, 1920.

Application filed September 23, 1919. Serial No. 325,773.

To all whom it may concern:

Be it known that I, RAY H. CLIFTON, a citizen of the United States, and a resident of East Peru, in the county of Madison and

5 State of Iowa, have invented a certain new and useful Timing Device, of which the following is a specification.

The object of my invention is to provide a timing device of simple, durable and inexpensive construction.

More particularly it is my object to provide a timing device adapted to be used in combination with an ignition system of an automobile for making and breaking a circuit of electrical current.

Still a further object is to provide a timing device comprising a casing, an eccentric member within said casing designed to be operated from the cam shaft of the automobile, a plurality of contact points within the casing so designed that when the eccentric member is rotated the contact points will be consecutively forced against contacts mounted on the outside of the casing for making a circuit.

A further object is to provide a timing device comprising a casing, an eccentric member rotatably mounted within the casing, and means for making and breaking a circuit of electrical current.

Still a further object is to provide a timer comprising a casing having slidable contact points yieldingly held out of operative position, an eccentric member rotatably mounted in said casing and so designed that the periphery of said eccentric member is always held against the inner end of said slidable points, whereby rotation of said eccentric member will force each of 40 said contact points outwardly until they engage resilient contact strips which are mounted on the outside of said casing.

With these and other objects in view my invention consists in the construction, arrangement and combination of the various parts of the device whereby the objects contemplated are attained, as hereinafter more fully set forth, pointed out in my claims and illustrated in the accompanying drawings, in which:

Figure 1 shows a front view of my timing device a portion thereof being shown in section to better illustrate the construction.

Fig. 2 shows a sectional view taken on

the line 2—2 of Fig. 1 showing the device as applied on the engine front.

Fig. 3 shows a side elevation of the closure member for my timing device.

Fig. 4 shows an enlarged, detail, sectional view of one of the contact points in its operative position.

Fig. 5 shows a modified form of my device; and

Fig. 6 shows a detail view of the binding post.

In the accompanying drawings I have used the reference numeral 10 to indicate generally a casing preferably made of insulating or non-conducting material.

The casing 10 is provided with an enlarged central opening 11. The casing 10 is provided with a recess 12 which is adapted to be received in a registering opening in the engine front 13.

The cam shaft of the automobile engine 75 extends into the casing 10. The casing 10 is provided with a plurality of spaced openings 15. A cover member 16 is designed to be received over the forward side of the casing. The cover is provided with a plurality of pins or lugs 17 which are designed to register with the openings 15 in the casing 10. The pins 17 provide means for holding the closure member over the casing.

Slidably mounted within the casing 10 are the contact points 18. The contact points 18 are received within the sleeve 19 having a flange 20 thereon.

The casing 10 is provided with an enlarged opening 21 on its inner side.

The contact point 18 has a head 22 thereon having a contracted portion therein 23.

A spring 24 is mounted over the sleeve 19 and received within the opening 21 in the casing. The spring rests against the flange 95 20 on one end and the head 22 on the other end. The spring forms a means for holding the contact points out of operative position.

Formed within the casing 10 is a screw-threaded opening 25 which is adapted to receive the screw-threaded sleeve 26. The screw-threaded sleeve is provided with a slot 27 near its lower end.

Received within the central opening of 105 the screw-threaded sleeve 26 is a binding post 28 having a head 29 thereon.

The binding post 28 is screw-threaded

so that the nut 30 may be placed thereon. When the nut 30 is screwed down tight, then the head 29 of the binding post 28 will become drawn into the central opening, causing the slot to slightly spread. It will be seen that this will cause the screw-threaded sleeve to become firmly wedged in the screw-threaded opening 25.

Secured around the binding post is an 10 electrical wire 31 which forms part of the ignition system of an automobile.

When the binding post is placed in the insulated casing member the screw-threaded sleeve 26 is screwed into the screw-threaded 15 opening 25 of the casing.

The sleeve 26 has the portion 32 thereon so that a wrench or pliers may be used in installing the sleeve in the casing. Placed between the portion 32 of the sleeve 26 and 20 the casing 10 is a resilient contact strip 33. The end of the contact strip 33 is so arranged that it fits over the opening of the sleeve 19 and above the outer end of the contact points 18.

25 Fixed to the cam shaft 14 is an eccentric member 34 which is held in place by the pin 35. The heads 22 of the contact points 18 set snugly against the periphery of the eccentric member 34.

30 A nut 36 on the cam shaft 14 holds the eccentric member in proper position.

A disk 37 having an inwardly extending flange 38 thereon is fixed to the eccentric member. The flange is placed equidistant 35 from the periphery of the eccentric member and is received within the contracted portion 23 of the head 22 of the contact points 18.

It will be seen that rotation of the cam 40 shaft 14 will rotate the eccentric member thereby forcing the contact points 18 outwardly until they engage the contact strips 33 and form a circuit. As the eccentric member is continuously rotated the contact 45 points engage the contact strips consecutively thus causing a circuit to be completed when the contact point strikes the contact strip.

It will be seen that the spring 24 will 50 tend to normally hold the contact point 18 out of engagement with the resilient contact strip 33. In order to be sure that the contact point will disengage the contact strip after the making of each circuit, the 55 flange 28 is provided so that if the spring 24 fails to withdraw the contact point, then the flange will draw the point out of engagement.

In the modified form of my device shown 60 in Fig. 5 of the drawings, 10 indicates the casing. Screw-threaded into the casing is a sleeve 39 which has the spring 24 around it.

The same kind of a contact point 18 is provided in the modified form of the device as 65 in the preferred form.

It will be seen that the casing 10 of the modified form is of conducting material so that it is necessary to completely insulate the binding post. In order to do this I have provided a socket or casing 40 which 70 is designed to be forced into the casing 10.

Within the socket 40 is placed the insulated material 41. Fixed in the insulated material 41 is the same binding post as I use in the preferred form of my device. 75

From the foregoing description it will be seen that I have provided a timing device with parts so arranged that it is impossible for them to become affected by wear and tear to such an extent that the device will 80 be inoperative.

By using the eccentric member as a medium for forcing the contact points outwardly until they engage the contact strips I get what I call a forced contact. Where 85 springs are used to obtain the contact, ordinary wear and usage make the springs lose their tension, so that the device does not operate in a satisfactory manner, but with my device I have a positive means for 90 both forcing the contacts into engagement and for withdrawing them from engagement.

It will be understood that some changes 95 may be made in the construction and arrangement of the parts of my device without departing from the essential features and purposes of my device, and it is my intention to cover by my claims any modified forms of structure or use of mechanical 100 equivalents which may be reasonably included within their scope.

I claim as my invention:

1. In a device of the class described, a casing of non-conducting material having a 105 plurality of sleeves mounted therein, contact points slidably mounted in said sleeves, resilient contact strips mounted on said casing and adapted to extend over said sleeves and to be spaced therefrom, means for yieldingly holding said contact points out of engagement with said contact strips, an eccentric member rotatably mounted in said casing, 110 adapted during its rotation to consecutively cause each of said contact points to engage said contact strips for making a circuit.

2. In a device of the class described, a casing of non-conducting material having a 115 plurality of sleeves mounted therein, contact points slidably mounted in said sleeves, resilient contact strips mounted on said casing and adapted to extend over said sleeves and to be spaced therefrom, means for yieldingly holding said contact points out of engagement with said contact strips, an eccentric member rotatably mounted in said casing, 120 adapted during its rotation to consecutively cause each of said contact points to engage said contact strips for making a circuit.

130

- cuit, and means for withdrawing said contact points from engagement with said contact strips.
3. In a device of the class described, a casing of non-conducting material having a plurality of sleeves mounted therein, contact points slidably mounted in said sleeves, resilient contact strips mounted on said casing and adapted to extend over said sleeves and to be spaced therefrom, means for yieldingly holding said contact points out of engagement with said contact strips, an eccentric member rotatably mounted in said casing adapted during its rotation to consecutively cause each of said contact points to engage said contact strips for making a circuit, a head formed on the inner end of said contact points, an eccentric member rotatably mounted in said casing, a fixed annular band spaced equidistant from the periphery of said eccentric member, and adapted to rotate with said eccentric member, a portion of said head adapted to be received between the under side of said band and the periphery of said eccentric member, whereby rotation of said eccentric member will consecutively force said contact points outwardly until they engage said contact strips, and said band will consecutively withdraw said contact points after the making of each circuit.
4. In a device of the class described, a casing of non-conducting material having a plurality of sleeves mounted therein, contact points slidably mounted in said sleeves, resilient contact strips mounted on said casing and adapted to extend over said sleeves and to be spaced therefrom, means for yieldingly holding said contact points out of engagement with said contact strips, an eccentric member rotatably mounted in said casing, adapted during its rotation to consecutively cause each of said contact points to engage said contact strips for making a circuit, a head formed on the inner end of said contact points, an eccentric member rotatably mounted in said casing, a fixed annular band spaced equidistant from the periphery of said eccentric member and adapted to rotate with said eccentric member, a portion of said head adapted to be received between the under side of said band and the periphery of said eccentric member, whereby rotation of said eccentric member will consecutively force said contact points outwardly until they engage said contact strips, means for limiting the outward movement of said contact points, and means for returning said contact points to position out of engagement with said contact strips.
5. In a device of the class described, a casing, a shaft operatively connected with suitable means for rotation, a plurality of sleeves mounted in said casing, contact points having heads thereon, slidably mounted in said sleeves, a contracted por-
- tion formed in said heads, springs mounted over said sleeves and adapted to yieldingly hold said contact points in one limit of their movement, insulated binding posts mounted upon said casing, resilient contact strips on said binding posts said strips being designed to rest over said sleeves and to be spaced slightly therefrom, an eccentric member fixed to said shaft, an annular band spaced equidistant from the periphery of said eccentric member, fixed to said eccentric member, said band being designed to be received in said contracted portion of said heads, whereby rotation of said shaft will rotate said eccentric member and said band, thereby causing said contact points to consecutively engage and disengage said contact strips to make and break a circuit.
6. In a device of the class described, a casing having a plurality of sleeves mounted therein, contact points slidably mounted in said sleeves, resilient contact strips mounted on said casing and adapted to extend over said sleeves and to be spaced therefrom, means for yieldingly holding said contact points out of engagement with said contact strips, an eccentric member rotatably mounted in said casing, adapted during its rotation to consecutively cause each of said contact points to engage said contact strips for making a circuit.
7. In a device of the class described, a casing provided with contact points slidably mounted therein, resilient contact strips mounted on said casing and adapted to extend over said contact points and to be spaced therefrom, means for yieldingly holding said contact points out of engagement with said contact strips, an eccentric member rotatably mounted in said casing, adapted during its rotation to consecutively cause each of said contact points to engage said contact strips for making a circuit.
8. In a device of the class described adapted for use with an ignition system for making and breaking a circuit, a casing having contact strips mounted thereon, contact points slidably mounted in said casing, means for yieldingly holding said contact points out of engagement with said contact strips, and for retracting the contact points after they have engaged with the contact strips, and means for causing said contact points to consecutively engage said contact strips for making a circuit.
9. In a device of the class described, a casing of non-conducting material having a plurality of sleeves mounted therein, contact points slidably mounted in said sleeves, resilient contact strips mounted on said casing and adapted to extend over said sleeves and to be spaced therefrom, means for yieldingly holding said contact points out of engagement with said contact strips,

- 4
- said last means also serving to withdraw the contact points, after they have engaged the contact strips, an eccentric member rotatably mounted in said casing adapted during its rotation to consecutively cause each of said contact points to engage said contact strips for making a circuit, and means for withdrawing said contact points from engagement with said contact strips.
10. In a device of the class described, a casing having a plurality of sleeves fixed therein, contact points slidably mounted in said sleeves, contact strips spaced adjacent to one end of said sleeves, means for yieldingly holding said contact points out of engagement with said contact strips, said last means also acting to retract the contact points after they have engaged the contact strips, a member rotatably mounted in said casing adapted during its rotation to consecutively cause a contact to be made and then broken between the various contact points and contact strips. 15 20

Des Moines, Iowa, September 5, 1919.

RAY H. CLIFTON.
